[57] CLAIM

The ornamental design for a thermometer sheath, as shown and described.

DESCRIPTION

FIG. 1 is a left side elevational view of a thermometer sheath showing my new design;

FIG. 2 is a top plan view thereof;

FIG. 3 is a front elevational view thereof;

FIG. 4 is a rear elevational view thereof;

FIG. 5 is a bottom and right rear perspective view thereof;

FIG. 6 is a rear and left-front perspective view thereof, the broken-line showing of a face and thermometer are environmental only and form no part of the claimed design.

FIG. 1

FIG. 3

FIG. 2

FIG. 6

FIG. 4

FIG. 5
